GAS TURBINE ENGINES

Neville Raymond Lloyd Quinn and Alexander Douglas Carmichael, Bristol, England, assignors, by mesne assignments, to Bristol Aero-Engines Limited, Bristol, England, a British company

Application March 21, 1955, Serial No. 495,502

Claims priority, application Great Britain April 1, 1954

8 Claims. (Cl. 230—114)

This invention relates to gas turbine engines of the kind (hereinafter referred to as the kind described) comprising a compressor system for compressing working fluid, said compressor system having more than one compression stage, combustion equipment for heating working fluid compressed by the compressor system, and a turbine system for driving the compressor system, said turbine system being arranged for operation by the working fluid heated by the combustion equipment. The turbine system may also drive an external load and may comprise two or more independently rotating rotors some or each of which is coupled to a compressor rotor.

By a "compression stage" is meant a passage of the working fluid past a power-driven axial-flow, centrifugal-flow or mixed-flow blade-row and may include a co-operating stationary blade-row whereby velocity head is converted into pressure head.

In engines of this kind, more particularly those in which all the moving compressor blades are driven at the same speed, difficulty is frequently encountered at low running speeds in that the flow of working medium through the lower pressure compression stages is insufficient to avoid surging. To overcome this difficulty it has been the practice to blow off working fluid from an intermediate compression stage into the atmosphere until the speed or the compression ratio of the compressor exceeds a value at which such blowing off may be stopped without danger of surging occurring.

Hitherto, the blowing off of working fluid from the compressor has been controlled by a speed- or pressure-ratio sensitive device acting upon a servo system to open or close blow-off valves, but this involves considerable complication, additional weight, and risk of defective operation, and the object of the present invention is to provide a valve-less system which permits working fluid to blow-off from an intermediate compression stage only until running conditions are reached at which such blowing off is no longer necessary. To this end the present invention broadly provides a gas turbine engine of the kind described and further comprising means defining a flow path communicating an intermediate pressure zone of said compressor system with a low pressure zone in or in communication with a main working fluid flow path through the engine in which low pressure zone there exists at all times during running of the engine a static pressure less than the static pressure in said intermediate zone, said low pressure zone being positioned downstream of a restriction in said main working fluid flow path, which restriction is such that it becomes or tends to become choked as the speed of the compressor system increases, said flow path defining means including a chamber having an inlet from said intermediate zone and an outlet to said low pressure zone which outlet is at a lesser radial distance from the axis of said chamber than said inlet, said chamber being arranged to rotate about its axis during operation of the engine, at a speed related to the speed of a compressor of the compressor system, the arrangement being such that below a predetermined speed

2

of said compressor a free vortex of working fluid is generated in the chamber, and above said predetermined speed a partially degenerated or totally degenerated vortex is generated in the chamber.

5 The compressor system may comprise a bladed compressor rotor having a number of blade rows, in which case the intermediate pressure zone is a zone between an adjacent pair of rows of blades.

In another case, however, the compressor system may 10 comprise a low pressure compressor rotor and a high pressure compressor rotor, in which case, the intermediate pressure zone may be at the exhaust end of the low pressure compressor, or it may be at an intermediate pressure stage of the low pressure or high pressure compressor

15 or in the case where the low pressure compressor or the high pressure compressor comprises a bladed rotor having a number of blade rows.

As will hereinafter be more fully explained, when a free vortex exists in the chamber a flow of working fluid

20 takes place from the intermediate zone through the chamber to the low pressure zone. When, however, a degenerated or partially degenerated vortex exists in the chamber blow-off of working fluid from the intermediate zone does not take place. Up to said predetermined speed of said compressor, therefore, working fluid

25 is blown off from the intermediate pressure zone but above the predetermined speed the blow-off ceases, the predetermined speed is chosen to be that speed of said compressor at which running conditions are such that blow-off

30 is no longer necessary, and no valve means is provided in the flow path defined between the intermediate pressure zone and the low pressure zone. The invention, therefore, provides a valve-less system which permits working fluid to blow off from an intermediate compression stage only until running conditions

35 are reached at which said blowing-off is no longer necessary.

In one form the present invention may consist in a gas turbine engine of the kind described, including a ring

40 of turbine nozzle guide blades, a driven rotor having an interior chamber bounded in each axial direction by walls which are surfaces of revolution about the axes of rotation of the rotor and which are substantially free from features likely to hinder free-vortex movement of a

45 gaseous medium in the chamber, means defining a first opening to the interior of the chamber, means defining a second opening to the interior of the chamber, said second opening being positioned at a lesser radial distance from the axis of rotation of said rotor than said

50 first opening, means defining an opening (hereinafter referred to as the third opening) to the main working fluid flow path through the engine at a position in the compressor system corresponding to partial compression of the working fluid during running of the engine, first con-

55 duct means connecting the third opening with said first opening, and second conduit means connecting said second opening with a low pressure zone in or in communication with a main working fluid flow path through the engine downstream of said ring of turbine nozzle guide

60 blades in which low pressure zone the static pressure during running of the engine is lower than the static pressure at the third opening, the radial distances between said first opening and the third opening and between said first opening and said second opening being so related

65 to the changing pressure differential set up between the pressure at the third opening and the pressure in said low pressure zone during variable speed running of the engine that a significant flow of working fluid takes place from said intermediate zone to the low pressure zone

70 through the third opening and the chamber and said conduit means only at speeds below a predetermined speed.

In another form, the present invention may consist in a gas turbine engine of the kind described including a ring of turbine nozzle guide blades and a driven compressor rotor having an intermediate compression stage, said rotor comprising axial-flow blading carried upon the outer periphery of the rotor, the rotor having an interior chamber bounded by the outer peripheral wall of the rotor and walls spaced apart axially of the rotor, said chamber communicating with said intermediate compression stage through a peripheral opening in the outer peripheral wall of the rotor, the chamber also communicating through a wall opening in one of said axially spaced walls nearer its axis of rotation than said peripheral opening with a low pressure zone in or in communication with a main working fluid flow path through the engine downstream of said turbine nozzle guide blades, in which zone, during running of the engine, the static pressure is lower than the static pressure at said peripheral opening, and said rotor also being provided in said chamber with air-movement-restricting means extending over a part only of the radial distance between said peripheral opening and said wall opening whereby, during running of the engine free-vortex movement of air in said chamber, where provided with air-movement-restricting means, is prevented, the walls of the remainder of said chamber being surfaces of revolution substantially free from features likely to hinder free-vortex movement of air therein, the radial extent of said air-movement-restricting means being selected so that below a predetermined speed of said rotor a free vortex of air is generated in said chamber, and above said predetermined speed a partially degenerated or totally degenerated vortex is generated in the chamber.

Two embodiments of the present invention will now be described by way of example with reference to the accompanying drawings whereof,

Figure 1 is a diagrammatic side elevation in cross-section of one gas turbine engine in accordance with the present invention,

Figure 2 is a diagrammatic side elevation in cross-section of another gas turbine engine in accordance with the present invention, and

Figure 3 is a diagrammatic showing of pressure ratios within the disclosed free vortex chamber, relative to rotary speeds.

The gas turbine engine shown diagrammatically in Figure 1 comprises a compressor system 1, having a rotor 2 with five stages of axial-flow blading and a stator 3, the compressor system delivering compressed air through an outlet 18 into combustion equipment 4 into which fuel is injected, for combustion, by burners 5 to heat the air compressed in the compressor system, and a turbine system 6 including a rotor 7 with axial-flow blading and nozzle guide blading 8, which turbine system receives all the products of combustion of the combustion equipment which products drive the turbine. The turbine rotor 7 is connected to the compressor rotor 2 by a hollow shaft 10 so that these parts rotate together. The exhaust gases from the turbine are discharged into the atmosphere along an exhaust duct 9.

To avoid surging in the compressor 1 during starting and slow speed running of the engine it is necessary to blow off air from an intermediate compression stage. In this example, air is blown off from the third compression stage through a number of similar equally spaced radially extending conduit means 11 each having an opening 12 at one end into a chamber 13 formed in the interior of the compressor rotor 2 and an opening 14 at the other end into the working-fluid passage 15 of the engine at the third compression stage, the conduit means 11 being positioned in the chamber 13. The blow-off air leaves the chamber 13 through a central opening 16 into the hollow shaft 10, and from the shaft passes through an opening 19 in the turbine rotor 7

into a low pressure zone 20 which is in communication with the working-fluid-passage 15 downstream of the turbine nozzle guide blades 8 and of the turbine moving blades. The hollow shaft 10, therefore, constitutes a further conduit means connecting the opening 16 with the zone 20.

The chamber 13 is bounded in the forward axial direction by a wall 21, and in the rearward axial direction by a wall 22, both these walls being surfaces of revolution relatively to the axis 17 and smoothly surfaced so as to be free of features likely to hinder free-vortex movement of air in the chamber 13.

During running of the engine the zone 20 has a lower static pressure than that which exists at the opening 14. Furthermore, the pressure ratio between a point in the working fluid passage of the engine in the region of the openings 14 and the zone 20, hereinafter referred to as P_{14}/P_{20} , has a drooping characteristic of the kind indicated by the curve A in Figure 3, in which compression ratio R is plotted against non-dimensional compressor speed $N/\sqrt{T}$. The reason for this is that as the compressor speed increases, the flow through the nozzle guide blades 8 becomes, or tends to become choked, with the result that the pressure ratio between the outlet of the compressor and the zone 20 (P_{18}/P_{20}) becomes, or tends to become, constant, while the pressure ratio between the outlet of the compressor and the region of the openings 14 (P_{18}/P_{14}) continues to rise approximately as the square of the compressor speed. Considering the ultimate state, in which

$$\frac{P_{18}}{P_{20}} = A \text{ and } \frac{P_{18}}{P_{14}} = B \cdot \left(\frac{N}{\sqrt{T}} \right)^2$$

35 A and B being constants,

it follows that

$$\frac{P_{14}}{P_{20}} = \frac{A}{B} \cdot \left(\frac{1}{N/\sqrt{T}} \right)^2$$

that is to say that P_{14}/P_{20} varies inversely as the compressor speed, and the curve A in Fig. 3 changes progressively from an approximation to a square-low curve to an approximation to a rectangular hyperbola.

When air passes into or out of the chamber 13 through the openings 12 or 16 a drop of pressure occurs across the opening concerned, and it will be appreciated that for a flow of air to pass through the chamber such pressure drops must be in the same sense, so that the mean of the pressures on the "inner" sides of the openings will be equal or approximately equal to the mean of the pressures on the "outer" sides of the openings according to whether the pressure drops through the openings are equal or unequal. Having established this preliminary relation it will be convenient in considering the operation of the system to compare the ratio of the "inner side" pressures with the ratio of the "outer side" pressures, these ratios being non-dimensional, so as to determine whether flow takes place, and if so, in which direction.

If, when the engine is running at a particular speed, the pressure ratio between the outer sides of the openings 12 and 16 as determined by the prevailing value of the pressure ratio P_{14}/P_{20} , is greater than the pressure ratio across a free vortex formed in the chamber 13 between the inner sides of the openings (the whirl velocity of the vortex at its outer periphery being equal to the angular velocity of the compressor rotor) then a flow of air will take place into the chamber through the openings 12 and out through the opening 16. As the speed of the engine increases, the pressure ratio across the free vortex increases, but the pressure ratio across the outer sides of the openings 12 and 16 increases less rapidly or decreases, for the reasons already explained, so that a condition is reached at which the two are equal. As this condition is

approached the flow through the chamber 13 falls rapidly and reaches a minimum value sufficient only to keep the free vortex in existence. Further progressive falling of the "external" pressure ratio results in the free vortex progressively degenerating into a forced vortex from its inner periphery outwardly, a very small flow being maintained out through the opening 16 during this period. When a state is reached at which the free vortex has become wholly converted to a forced vortex, flow through the chamber 13 ceases, this being the case when the difference in pressure between the outer sides of the openings 12 and 16 is equal to the difference between the centrifugal head pressures corresponding to the radii at which the openings 12 and 16 are situated. If the external pressure ratio continues to fall below the forced vortex pressure ratio a small flow will occur into the chamber 13 through the opening 16 and out through the opening 12, but this flow will start to destroy the forced vortex since this latter is only maintained by the boundary layer friction against the walls of the chamber. In other words, the main body of air in the chamber 13 will progressively lose rotational speed relatively to the walls of the chamber as the air-flow through the chamber increases, so that the excess of centrifugal head over the external pressure difference remains small until the external pressure at the opening 16 exceeds the external pressure at the opening 12, but this condition is of course, never reached during the operation of the engine.

When the speed of the engine decreases again the process reverses, that is to say, first a forced vortex is generated and this gradually changes to a free vortex, and only when this had been fully established can any substantial flow of blow-off air take place.

It will be clear, therefore, that by suitably choosing the radial distances of the openings 12 and 16 from the axis of rotation it can be arranged that blowing off of a significant quantity of air occurs only at engine speeds below a selected value appropriate to guard against surging in the compressor. This is illustrated in Figure 3 in which the curves B₁, B₂ and B₃ show for three values of the ratio of the inside and outside diameters of the free vortex chamber, the variation with speed of the pressure ratio between the inside and outside peripheries of a free vortex therein. Neglecting the centrifugal pressure head generated between the openings 12 and 14, which may if necessary be balanced by the provision of vanes 37 on the downstream face of the turbine rotor 7 in the zone 20, the point of intersection of a curve B with the curve A denotes a condition at which the pressure ratio between the blow-off openings 12 and the zone 20 is just equal to the pressure ratio between the inside and outside peripheries of a free vortex in the chamber 13. At this speed therefore, and at all higher speeds, no significant blow-off flow can take place through the chamber 13, but at lower speeds there is an excess of pressure ratio available, as indicated, for example, by the ordinate 40 applicable to the curve B₂, which will cause a blow-off flow of air through the chamber 13.

The quantity of air which is blown off at any particular engine speed depends upon the excess pressure difference represented by the ordinate 40 available to cause the flow and upon the resistance of the flow path, as determined by the cross-sectional areas of the openings and ducts through which the flow takes place and any other sources of pressure loss.

The conduit means or tubes 11 are of such a radial extent into the rotating chamber 13 that the centrifugal head within the chamber 13 at the critical speed, when surging begins, is such as to allow by-passing of fluid through tubes 11, hollow shaft 10 and openings 19 to the zone of lower pressure 20.

Figure 2 shows a somewhat different arrangement of the vortex chamber in an engine which is basically the same as that shown in Figure 1 and in which the same parts are denoted by the same reference numerals.

In this arrangement, the compressor rotor 2 carrying upon its outer periphery five stages of axial-flow blading is provided with an interior chamber 13 communicating with the working-fluid-passage 15 at the third compression stage through a ring of peripheral openings 30 in the outer peripheral wall of the rotor. The chamber 13 also communicates through a wall opening 31, concentric with the axis of rotation, and in the rear wall 22 of the chamber and through a hollow bore 32 in the shaft 10 with a zone 20 which is in communication with the working-fluid-passage 15 of the engine downstream of the turbine 6 and the ring of turbine nozzle guide blades 8 and, therefore, during running of the engine has a lower static pressure than that which exists at the peripheral openings 30. The rotor 2 is also provided in the chamber 13 with a number of radial vanes 34 which extend from the axis of rotation over a part only of the radial distance between the openings 31 and the openings 30. The vanes 34 may also have extended parts 41 located in the bore 32 of the shaft 10. The remaining parts of the side walls 35 and 36 and of the outer peripheral wall are surfaces of revolution substantially free from projections or other features likely to hinder free-vortex movement of air in that part of the chamber not provided with vanes.

25 The operation of this arrangement is very similar to that of Figure 1 in that the ratio of the inside and outside diameters of the free vortex chamber, which may be adjusted by varying the radial extension of the vanes 34, is so chosen that the free vortex breaks down at an engine speed at which blowing-off of air from the compressor is no longer required.

If desired, radially extending vanes 37 may be provided on the downstream face of the turbine rotor 7 to balance the centrifugal pressure head generated through the vanes 34.

We claim:

1. A gas turbine engine comprising a multi-stage compressor having a rotor and an intermediate pressure zone, combustion equipment and a turbine through which a working fluid passes in sequential flow and having a critical speed below which surging takes place in the compressor and a restriction in said sequential flow downstream of said intermediate pressure zone so constructed as to become progressively more choked as the speed of the compressor increases providing a pressure zone downstream of the restriction and having a pressure less than said intermediate zone, blow-off path means comprising a chamber encircling the axis of rotation of said compressor and rotated by the compressor at the speed of the compressor, said chamber having an inlet communicating with the intermediate pressure zone, having a passage through said rotor and having an outlet communicating with the lower pressure zone, said inlet being positioned at a substantially greater radial distance from said axis than said outlet, and means attached to said chamber and rotating with said chamber for selecting the centrifugal head developed on the air within said rotating chamber to such a predetermined value that when the engine is running below its critical speed the fluid from the intermediate pressure zone enters the chamber and forms a free vortex therein and flows through the outlet to the lower pressure zone and when the engine is running at or above its critical speed a forced vortex is formed in the chamber the centrifugal head of which is sufficient to prevent the working fluid from entering the chamber.

2. A gas turbine engine as claimed in claim 1, wherein said communication between said outlet and lower pressure zone means comprises a hollow shaft by which said rotor is mounted for rotation, said shaft also carrying a turbine rotor, and the interior of the shaft opening to a zone immediately on the downstream side of said turbine rotor, which zone constitutes said low pressure zone and is in communication with the main working fluid flow path through the engine downstream of the turbine rotor blades.

3. A gas turbine engine as claimed in claim 2, wherein a plurality of radially extending vanes are provided on the downstream face of said turbine rotor, which vanes balance the centrifugal pressure head developed between said inlet and outlet during operation of the engine.

4. A gas turbine engine comprising a multi-stage compressor having a rotor and an intermediate pressure zone, combustion equipment and a turbine through which a working fluid passes in sequential flow and having a critical speed below which surging takes place in the compressor and a restriction in said sequential flow downstream of said intermediate pressure zone so constructed as to become progressively more choked as the speed of the compressor increases providing a pressure zone downstream of the restriction and having a pressure less than said intermediate zone, blow off flow path means comprising a chamber encircling the axis of rotation of said compressor and rotated by the compressor at the speed of the compressor, said chamber having an inlet communicating with the intermediate pressure zone and an outlet communicating with the lower pressure zone, said inlet being positioned at a substantially greater radial distance from said axis than said outlet whereby when the engine is running below its critical speed the fluid from the intermediate pressure zone enters the chamber and forms a free vortex therein and flows through the outlet to the lower pressure zone and when the engine is running at or above its critical speed a forced vortex is formed in the chamber the centrifugal head of which is sufficient to prevent the working fluid from entering the chamber, a ring of turbine nozzle guide blades on the turbine, said rotor comprising axial-flow blading carried upon the outer periphery of the rotor, said chamber comprising the outer peripheral wall of the rotor and walls spaced apart axially of the rotor, said inlet comprising a peripheral opening in the outer peripheral wall of the rotor, said outlet being formed in one of said axially spaced walls said low pressure zone in or in communication with a main working fluid flow path being downstream of said turbine nozzle guide blades, in which low pressure zone, during running of the engine, the static pressure is lower than the static pressure at said peripheral opening, air-movement-restricting means on said rotor within said chamber and extending over a part only of the radial distance between said peripheral opening and said wall opening whereby, during running of the engine the free-vortex movement of air in said chamber, where provided with air-movement-restricting means, is prevented, the walls of the remainder of said chamber being surfaces of revolution substantially free from features likely to hinder free-vortex movement of air therein, the radial extent of said air-movement-restricting means being selected so that below a predetermined speed of said rotor a free vortex of air is generated in said chamber, and above said predetermined speed a partially degenerated or totally degenerated vortex is generated in the chamber.

5. A gas turbine engine as claimed in claim 4, wherein said air-movement-restricting means comprises radially extending vanes.

6. A gas turbine engine as claimed in claim 5 wherein said vanes have extended parts which are located in said communication between said outlet and lower pressure zone.

7. A gas turbine engine as claimed in claim 4, wherein said turbine is provided with a rotor and said rotor is provided on its downstream face with a plurality of radially extending vanes which balance the centrifugal pressure head developed through said air-movement-restricting means.

8. A gas turbine engine comprising a multi-stage compressor having a rotor and an intermediate pressure zone, combustion equipment and a turbine through which a working fluid passes in sequential flow and having a critical speed below which surging takes place in the compressor and a restriction in said sequential flow downstream of said intermediate pressure zone so constructed as to become progressively more choked as the speed of the compressor increases providing a pressure zone downstream of the restriction and having a pressure less than said intermediate zone, blow off flow path means comprising a chamber encircling the axis of rotation of said compressor and rotated by the compressor at the speed of the compressor, said chamber having an inlet communicating with the intermediate pressure zone and an outlet communicating with the lower pressure zone, said inlet being positioned at a substantially greater radial distance from said axis than said outlet whereby when the engine is running below its critical speed the fluid from the intermediate pressure zone enters the chamber and forms a free vortex therein and flows through the outlet to the lower pressure zone and when the engine is running at or above its critical speed a forced vortex is formed in the chamber the centrifugal head of which is sufficient to prevent the working fluid from entering the chamber, air-movement-restricting means on said rotor within said chamber and extending over a part only of the radial distance between said inlet and outlet whereby, during running of the engine the free-vortex movement of air in said chamber, where provided with air-movement-restricting means, is prevented, the inner surfaces of the remainder of said chamber being surfaces of revolution substantially free from features likely to hinder free-vortex movement of air therein, the radial extent of said air-movement-restricting means being selected so that below a predetermined speed of said rotor a free-vortex of air is generated in said chamber, and above said predetermined speed a partially degenerated or totally degenerated vortex is generated in the chamber.
